(57) **CLAIM**

The ornamental design for a canister, as shown and described.

DESCRIPTION

FIG. 1 is a top, front, and right perspective view of the canister;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a top, rear, and left perspective view thereof.

The broken line showing of the fastening hardware, mounting bracket, and other portions of the canister form no part of the claimed design.
